UNITED STATES PATENT OFFICE.

WILLIAM P. DUN LANY, OF CHICAGO, ILLINOIS, ASSIGNOR TO SEARS, ROEBUCK AND CO., OF CHICAGO, ILLINOIS, A CORPORATION OF NEW YORK.

DOLL.

1,417,810.

Specification of Letters Patent. Patented May 30, 1922.

Application filed May 25, 1918. Serial No. 236,498.

To all whom it may concern:

Be it known that I, WILLIAM P. DUN LANY, a citizen of the United States, residing at Chicago, in the county of Cook and 5 State of Illinois, have invented certain new and useful Improvements in Dolls, of which the following is a specification.

One of the objects of this invention is to simplify and improve the construction of, 10 and the means of mounting, the movable eyes of a so-called sleeping doll.

Another object of the invention is to provide the head of the doll with a detachably secured crown section which is arranged to 15 be removed to give access to the eyes within the head, so as to permit of mounting, adjusting, or repairing the eyes.

The invention also aims to provide a removable crown section having attached 20 thereto the hair or wig to cover the head, the crown section and wig being readily removable as a unit to permit of the substitution of a wig of different type or color. The crown section also forms a rigid backing 25 for the wig which conduces to greater durability.

In the accompanying drawings, Figure 1 is a vertical central sectional view through 30 a doll head illustrating the features of my invention. Fig. 2 is a fragmental top plan view of the head with the wig removed to illustrate the removable crown section. Fig. 3 is a bottom plan detail view of the removable crown section. Fig. 4 is a horizontal 35 sectional view through the head to illustrate the eye construction. Figs. 5 and 6 are enlarged detail views of the eyes, Fig 5 being a plan view, and Fig. 6 an end view.

In the drawings the doll head as a whole 40 is designated 10 and it may be composed of any desired material. At the proper places there are provided apertures 11 representing eye sockets, and within the head behind these sockets is mounted a unitary eye-ball structure which comprises two portions 12 45 representing the eye-balls and a connecting portion 13. These portions 12 and 13 are made of a single piece of sheet metal which is stamped or formed into the proper shape. 50 The eye-ball portions 12 are of semispherical shape, while the connecting portion in the present instance is of tubular formation. The outer side edges of the eye-ball portions 55 are provided with apertures 14 which are located concentric with the spherical sur-

faces of the eye-balls, and these apertures are adapted to receive a supporting device which is preferably in the form of a single piece of wire 15 running through the apertures and through the cylindrical connecting portion 13, the ends of the wire being bent rearwardly to lie closely along the inner side walls of the head. These wire ends are preferably secured by being imbedded in a quantity of relative frangible material 60 such as plaster 16, which is applied to the side walls of the head over the ends of the wires.

An arm 17 carrying a weight 18 at its end is attached to the connecting portion 13 in 70 such relation to the eye-balls 12 as to cause the lower portions of the eye-balls to be exposed through the apertures 11 when the doll is in upright position and to cause the upper portions of the eye-balls to be exposed through said apertures when the doll is lying on its back. The lower eye-ball 75 portions are painted, lithographed or otherwise suitably treated to imitate human eyes, while the upper portions are treated to represent the eye-lids, so that when the doll is lying on its back it appears to be asleep, as is common in the art.

In the top of the head there is a relatively large opening 19 in which a removable 80 crown section 20 fits, the edges of the opening and section being beveled or otherwise suitably shaped to limit the inward movement of the crown section. The preferred means for securing the crown section in 85 place comprises a suitable number of yielding snap members or latches 21 secured to the crown section and arranged to engage the inner surface of the head adjacent to the opening 19 therein. Preferably these 90 spring arms are all formed integral with a central metallic plate-like portion 22, which is suitably secured to the lower side of the crown section 20. The ends of the latch members 21 are turned downwardly and inwardly toward the center of the crown section, so that the mere act of pressing the crown section into place causes the latch members to yield and finally engage the inner 95 wall of the head proper.

To the outer face of the crown section is secured a suitable wig 23 which may comprise a layer 24 of fabric or the like to which the hair is secured. In order to insure that the crown section will always be assembled 100 105 110

in the same position, and also to prevent accidental rotation thereof, there is provided an inter-engaging lug or recess 25, 26, on the abutting surfaces of the crown section 5 and the head.

To remove the crown section it is only necessary to insert a sharp implement at the edge of said section and pry upwardly, the 10 spring arms 21 yielding to allow such withdrawal of the section. The removal of the crown section permits convenient access to the eyes for mounting, repairing or adjusting the latter.

By providing the crown section and the 15 wig as a unitary device, greater convenience in manufacture or assembling of the parts is attained. Furthermore, in use the crown section forms a rigid backing for the wig which resists inward pressure by a child 20 playing with the doll so that greater durability of the wig is effected.

I claim as my invention:

1. A hollow doll head having eyes movably mounted within the head and having 25 a hole in the upper portion of the head through which the eyes may be mounted or repaired, a substantially flat rigid member closing said hole, disengageable means for securing said member in place, and a wig 30 affixed to the outer side of said member and removable therewith from the main portion of the head.

2. A doll head having an opening in the crown thereof, a removable rigid crown section 35 fitting in said opening, a plurality of spring catches attached to the crown section and arranged to engage the inner surface of the head adjacent to said opening for securing the crown section in place, and a wig 40 secured to the outer surface of the crown section.

3. A doll head, having an opening in the crown thereof, a rigid crown section removably fitting in said opening, yieldable means 45 for securing said section in place, and an eye structure mounted in and entirely supported by the body of said head, whereby removal of said crown section gives access to said eye structure.

50 4. A doll head, having an opening in the crown thereof, a rigid crown section removably fitting in said opening, yieldable means for securing said section in place, means for preventing rotation of said section, and a 55 wig secured to the outer face of said section.

5. A doll head having apertures representing eye sockets, a unitary eye structure located within the head behind said sockets

and comprising a pair of eye balls and a portion connecting said eye balls, all formed 60 from an integral piece of sheet metal, a weight attached to the eye structure for turning the latter, and means for pivotally supporting said eye structure.

6. A hollow doll head having apertures 65 representing eye sockets, a unitary eye structure located within the head behind said sockets and comprising a pair of eye balls and a portion connecting said eye balls, said eye structure being formed of an integral 70 piece of sheet metal, the outer side edges of the eye balls having apertures therethrough, a piece of wire passing through said apertures and having its ends extending along the inner side walls of the head, means for 75 securing said ends in place, and a weight eccentrically attached to the eye-ball structure for causing the latter to turn on said wire.

7. A hollow doll head having an eccentrically weighted eye-ball structure therein, and means for pivotally supporting said structure comprising two wire portions carrying the structure and lying along the inner side walls of the head and two quantities of 85 plaster overlying said wire portions and adhering to the walls of the head for securing the wire portions in place.

8. A doll head, having apertures representing eye sockets, an eye structure pivotally mounted adjacent said sockets, an opening in said head, a rigid removable cover fitting in and closing said opening, and a wig attached to said removable cover; whereby removal of said cover permits adjustment or repair of 95 said eye structure, and replacement of said cover by a similar cover carrying a different style of wig.

9. A doll head having, in combination, a body portion having an aperture cut in the 100 top portion of the crown, a plate-like section adapted to close said aperture, said section having beveled edges to prevent inward displacement and carrying resilient means adapted to snap in position and prevent outward displacement.

10. A doll head having, in combination, a body having an aperture in the top portion of the crown, a section adapted to close said aperture, a wig fastened to said section and adapted to overlie said crown, and means carried by said section to secure it to the body.

In testimony whereof, I have hereunto set my hand.

WILLIAM P. DUN LANY.
